UNITED STATES PATENT OFFICE.

EDWARD H. HORSEY, OF CHICAGO, ILLINOIS.

EMBALMING APPARATUS.

SPECIFICATION forming part of Letters Patent No. 416,223, dated December 3, 1889.

Application filed December 24, 1888. Serial No. 294,549. (No model.)

To all whom it may concern.

Be it known that I, EDWARD H. HORSEY, a citizen of the Dominion of Canada, residing in Chicago, in the county of Cook and State 5 of Illinois, have invented a new and useful Improvement in Embalming Apparatus, of which the following is a specification.

My invention relates to the art of embalming.

10 The object of my invention is to provide a conveniently-portable embalming apparatus which may be packed in a small space, so that it may be used on shipboard as well as on land, and which may be used without in any 15 way disfiguring or mutilating the body.

My invention consists, primarily, in a flexible air and liquid tight embalming-sack, preferably made of rubber, rubber cloth, tarpaulin cloth, or other suitable impervious 20 cloth, and having a mouth or opening through which the body to be embalmed may be carried into the sack on a suitable truck for supporting it. The mouth or opening of the sack through which the body is inserted is 25 furnished with set-screws and clamping-jaws to close it air-tight after the body is placed in the sack. The sack is furnished at its opposite end with a nozzle or orifice adapted to be connected with an air-pump for exhaust- 30 ing or partially exhausting the air from the embalming-sack, so as to form a partial vacuum therein. After the air has been partially pumped out of the embalming-sack the nozzle of the sack is connected to a vessel con- 35 taining the embalming vapor or gas in a compressed form. The body-supporting carriage not only serves to roll or convey the body into the flexible embalming-sack, but to support the same near the longitudinal center of 40 the sack during the embalming operation, and thus prevent the body from lying upon or coming in contact with the flexible sack, so that the embalming vapor or gas may act equally upon the whole surface of the body. 45 To prevent the flexible embalming-sack from coming in contact with the surface of the body when the air is being pumped out of the sack, I provide the sack with light hoops, springs, or distending devices, preferably on 50 the interior thereof; and for the same purpose, also, and to insure against any possible

mutilation or discoloration of the face by contact with the rubber or flexible sack, I provide a face-mask. This face-mask may be attached to the body; but it is preferably attached to the truck and supported thereby over the face. The truck or body supporting device is made (or preferably made) in hinged sections, so that it may be folded into a compact space. It is provided (or preferably provided) 55 with wheels, and they should be of rubber or furnished with rubber tires to prevent any danger of cutting or injuring the sack as the truck is rolled into the same. The springs or sack-distending devices before mentioned 60 serve not only to prevent the collapse of the sack against the body when the air is exhausted, but also to hold the sack distended while the body-truck is being rolled or inserted therein. The embalming vapor or gas 70 employed may be a simple article of commerce and manufactured commercially, or it may be made by the undertaker at his place of business, and then carried in a highly-compressed form in a suitable gas 75 holder or vessel to the house or place where the embalming is to be done. The gas holder or vessel containing the embalming-vapor may be readily connected to the embalming-sack after the body has been inserted therein, 80 the sack closed air-tight, and the air exhausted therefrom. A sufficient quantity of vapor or gas for embalming one body may be compressed into an ordinary gas holder or vessel of one or two cubic feet capacity. After the 85 embalming vapor or gas has been discharged into the embalming-sack under pressure, according to my invention, the pressure of the gas or vapor causes it readily to penetrate into and through the tissues of the body. 90 The previous exhaustion of the air from the embalming-sack and from the body contained therein by means of the air-pump greatly facilitates the subsequent penetration of the embalming vapors or gases into and through 95 the tissues of the body. To facilitate the partial exhaustion of air from the body, as well as the penetration of the embalming vapors or gases into the body, I prefer to insert elastic esophageal and rectal tubes. 100

In cases where it is desired to hasten the embalming process and complete the opera-

tion in a short time weights may be placed upon the flexible embalming-sack, and thus increase the pressure of the vapor or gas and facilitate its penetration into and through the tissues.

5 In the accompanying drawings, which form a part of this specification, and in which similar letters of reference indicate like parts, Figure 1 is a side elevation of an apparatus embodying my invention. Fig. 2 shows the compressed embalming gas or vapor holder. Fig. 3 is a plan view of the flexible embalming-sack; Fig. 4, an enlarged longitudinal vertical section showing the sack connected with the gas or vapor holder. Fig. 5 is an enlarged detail view showing the clamp or device for closing the mouth of the sack through which the body is inserted. Fig. 6 is a plan view of the same. Fig. 7 is an enlarged cross-section through one of the clamp-screws. Fig. 8 is a plan view of the body truck or carriage. Fig. 9 is a detail view of one of the sack-distending springs or hoops; and Fig. 10 is an elevation of the sack, showing weights placed thereon to increase the pressure of the embalming vapor or gas therein. Fig. 11 shows the disk or funnel for closing the mouth around the esophageal and rectal tubes.

30 In the drawings, A represents the flexible embalming-sack, preferably of rubber or other cloth; B, the truck for supporting the body therein during the embalming operation; C, the air-pump, and D the compressed embalming gas or vapor holder. The flexible sack A has a large mouth or opening *a* at one end, through which the body on the body-truck may be rolled or inserted. This mouth or opening is closed air-tight by the clamps *a'* and clamp-screws *a*³. The clamps *a'* *a*² may, if desired, be hinged or jointed together at their ends, as shown at *a*⁵. The lips or edges *a*⁶ *a*⁷ of the rubber sack at the mouth thereof may be preferably formed with a 35 rib *a*⁸ and groove *a*⁹ where they are clamped together by the screws *a*³, so as to form a more perfect joint. At or near the opposite end the sack A is furnished with a pipe or nozzle F, having a coupling *f*, by which it is adapted 40 to be connected with the pipe *c* of the air-pump C and with the pipe or nozzle *d* of the gas-holder D. The nozzle F is further provided with a cock or valve *f'* for closing the same. The gas or vapor holder D is also furnished with a cock or valve *d'*. The body-truck B is preferably made in three folding sections connected together by hinges *b* and by hooks or devices *b'* for rendering the joints rigid, so as to properly support the body. The 45 wheels *B'* of the truck B are furnished with rubber tires *B*², so that the wheels will not cut or infringe the flexible sack A when the body-truck is being rolled into the sack. The truck B is further provided with a face-mask G to 50 protect the face from contact with the flexible sack A. This mask should be removably attached to the truck, so that it may be put in

place after the body is on the truck. The truck is further provided at intervals with straps *b*² for securing the body thereto and with a neck 70 or head rest *b*³.

H H are the hoops, preferably made of spring or flexible material, for holding the sack distended. The ends of the hoop are preferably connected together by a loop *h* 75 and set-screw *h'*, so that the hoop may be readily adjusted to different diameters, as may be required to properly distend the sack for the reception of bodies of different sizes. The hoops H are placed loosely in the sack 80 and may be removed when desired.

The truck is an open frame-work having just enough cross-pieces *b*⁴ to properly support the body, so that the embalming gas or vapor may have access to the whole surface 85 of the body. The wheels *B'* of the truck serve to support the body in the sack at a distance above the bottom of the sack as the apparatus rests upon the floor or platform, so that the embalming gas or vapor may have access beneath the body. The diameter of the wheels should preferably be in practice about six inches, though their dimensions may be varied.

When not in use the whole apparatus may 95 be folded very compactly. The sections of the truck when folded together may be inserted in the flexible sack and then the flexible sack doubled or folded around the same. The whole apparatus is thus not only very 100 compact, but it is light and may be readily carried by a single person.

K represents the end of the esophageal tube projecting from the mouth. This should 105 preferably be about one-half inch in diameter. The tube K has a coupling *k*, by which it may be connected with the nozzle of a gas-holder and the gas thus forcibly injected into the interior of the abdominal cavity. This may be done, if desired, after the body is removed from the sack.

For use at sea the embalming-sack should be made of stronger and heavier material, so that it may serve as a casket for containing the body until the ship arrives at port. The 115 sack A may be provided with handles for convenience in handling when containing the body.

The weight before referred to for increasing the pressure of the gas or vapor is indicated in Fig. 10 at N.

In Fig. 11 the esophageal tube K is shown as provided with a conical-shaped flange, disk, or funnel *k*² for closing the mouth and nostrils when the gas-holder is connected directly with the tube K for injecting the gas into the abdominal cavity. A strap *k'* may be employed to hold the rubber funnel or dam in place.

I claim—

1. The portable foldable apparatus for subjecting bodies internally and externally to the action of embalming-gas under pressure, consisting of an air-tight inclosing-sack flexi-

ble upon all sides, having an opening for the insertion of the body, and furnished with means for closing such opening air-tight after the body is inserted, a foldable body-supporting frame within said sack and provided with wheels for supporting the body above the bottom of the sack, so that the embalming-gas may have access all around the body, said wheels also serving to roll the body and body-supporting frame out of and into the sack, said sack being furnished with a tube for the admission of the embalming-gas under pressure, so that the gas can be forced into the internal cavities of the body through suitable esophageal or rectal tubes, substantially as specified.

2. The portable foldable apparatus for subjecting bodies internally and externally to the action of embalming-gas under pressure, consisting of an air-tight inclosing-sack flexible upon all sides, having an opening for the insertion of the body, and furnished with means for closing such opening air-tight after the body is inserted, a foldable body-supporting frame within said sack and provided with wheels for supporting the body above the bottom of the sack, so that the embalming-gas may have access all around the body, said wheels also serving to roll the body and body-supporting frame out of and into the sack, said sack being furnished with a tube for the admission of the embalming-gas under pressure, so that the gas can be forced

into the internal cavities of the body through suitable esophageal or rectal tubes, said foldable body-supporting frame having hinges or joints furnished with devices for rendering them rigid, and said frame and sack being adapted to fold up together in a compact space, substantially as specified.

3. In an embalming apparatus, the combination of an inclosing-sack flexible upon all sides, and furnished with an opening at one end for the insertion of the body, and provided with clamps for closing such opening air-tight, with a wheeled supporting-frame for the body, whereby the body may be supported above the bottom of the sack, so that the embalming-gas may have access all around the body, and whereby the body may be rolled in and out of the sack without marring the body by contact with the sack, substantially as specified.

4. In an embalming apparatus, the combination of an inclosing case or sack flexible upon all sides, having an opening for the insertion of the body, and provided with clamps for effecting an air-tight closure of such opening, and hoops for distending the sack or case, with a support for the body, substantially as set forth.

EDWARD H. HORSEY.
